UNITED STATES PATENT OFFICE.

JOHN F. KITCHEN, OF ERIE, PENNSYLVANIA.

GUN-CLEANER ATTACHMENT.

1,237,056.

Specification of Letters Patent. Patented Aug. 14, 1917.

Application filed March 23, 1917. Serial No. 156,876.

To all whom it may concern:

Be it known that I, JOHN F. KITCHEN, a citizen of the United States, residing at Erie, in the county of Erie and State of Pennsylvania, have invented certain new and useful Improvements in Gun-Cleaner Attachments, of which the following is a specification.

This invention relates to gun cleaning implements, and has for its object to provide an improved attachment for joining the several well known forms of gun cleaners such as wire and bristle brushes, swabs, etc., to an operating handle, comprising a suitable 15 rod or staff which may be cut by the gunner in the field.

Another object of this invention is to provide in combination with any one of the attachable gun cleaning units, suitable hand holding means while the staff is being attached for use.

With these and other objects in view, the present invention consists in the combination and arrangement of parts as will be 25 hereinafter more fully described, shown in the accompanying drawings, and particularly pointed out in the appended claims, it being understood that changes in the form, proportion, size, and minor details 30 may be made within the scope of the claims without departing from the spirit or sacrificing any of the advantages of the invention.

In the drawings Figure 1, is a side elevation, partly in section, showing the device, with one form of cleaner attached thereto.

Fig. 2, shows the device in section with another form of cleaner in vertical elevation.

Fig. 3, is an enlarged longitudinal section of the device.

Like characters of reference designate corresponding parts in all the figures of the drawings.

In carrying out the present invention, I provide a tubular form of, preferably, non-corrosive metal which I shall designate as a union. This union 1, has one end provided with a comparatively small screw threaded socket 5, for the reception of the 45 stem 9, of a well known form of gun-cleaner, and its opposite end is provided with a larger screw threaded socket 2, for the reception of the wooden rod or staff 10. The

threads 3 of the socket 2 being formed with 55 a relatively sharp pitch, to facilitate penetrating the wood comprising the rod 10.

Passing through the union 1, at right angles thereof, is an aperture 7, having screw threads 8, therein, of the same diameter 60 and pitch as the threads in socket 5, to enable it to receive the screw threaded stems of the various standard cleaners, as shown in Fig. 2.

One of the essential features of this invention, resides in its adaptability to be attached without the use of tools, to a cleaning rod formed from a sapling, or limb of a tree, cut by the gunner in the field, thereby eliminating the necessity of carrying a 70 cleaning rod on gunning expeditions, and in so using the device, a rod 10 is prepared from any suitable wood and is adapted to be threaded into the socket 2. In this operation, for the purpose of providing means 75 for better holding the union 1, I insert into the aperture 7, of the union 1, the well known form of cleaner 12, as shown in Fig. 2. This affords a suitable hand holding means to maintain the union 1, from turning while the rod 10, is being screwed into the socket 2. In case the rod 10, should by accident become broken off short within the socket 2, leaving insufficient projection for unscrewing the same, the union 1 can be 85 heated sufficiently to burn out the short end of the rod 10, without injury to the union 1.

From the foregoing description, the use of my invention will be easily understood by those skilled in the art.

What I claim as my invention and desire to secure by Letters Patent is:

1. A gun cleaning device comprising a union having two screw threaded sockets in axial relation, a solid core portion intermediate of said sockets, and a screw threaded aperture passing transversely through the core portion.

2. A gun cleaning device comprising a union having two screw threaded sockets of 95 different diameters in axial relation, a solid core portion intermediate of said sockets, and a screw threaded aperture passing transversely through the core portion.

3. A gun cleaning attachment comprising 105 a union having two screw threaded sockets in axial relation, adapted to connect a cleaning swab with an operative handle, and de-

tachable means for holding the union against turning while attaching said operative handle, substantially as described.

4. In a gun cleaning device the combination of a cleaning swab with means of attaching a temporary operating handle to said swab, comprising a union having screw threaded end sockets in axial relation, and a screw threaded aperture transversely therethrough.

5. A gun cleaning device comprising a union adapted to connect a cleaning swab

with an operative handle having screw threaded end sockets, a solid core portion intermediate of said sockets and a screw ¹⁵ threaded aperture passing transversely through the core portion.

In testimony whereof I have affixed my signature in presence of two witnesses.

JOHN F. KITCHEN.
